TRAVELING WAVE ELECTRON DISCHARGE DEVICES

John M. Osepchuk, Peabody, and Roy A. Paananen, Needham, Mass., assignors to Raytheon Company, a corporation of Delaware

Application October 27, 1953, Serial No. 388,473

12 Claims. (Cl. 315—39.3)

This invention relates to electron discharge devices and more particularly to methods and means of construction of electron discharge devices of the traveling wave type having lossy material therein.

In electron discharge devices of the traveling wave type, wherein signal waves traveling along a network interact with electrons moving along paths adjacent to the network to produce amplification or oscillation, it is often desirable to introduce signal-absorbing material into the electron discharge device for the purpose of absorbing unwanted signals producing the wrong frequency or phase of interaction with the electron stream. Previously, lossy material had been painted or sprayed on various parts of the electrode structure. This was not satisfactory, since the lossy material tended to flake off after the electron discharge device was evacuated, was difficult to free from gas, and was difficult to accurately apply in the desired region to the desired thickness.

This invention discloses the discovery of a particularly desirable lossy material for use in electron discharge devices. The preferred embodiment of this material is pure iron. However, it is to be clearly understood that the invention is not limited thereto, but rather other ferro-magnetic materials may be used.

This invention further discloses that such material may be applied to the desired parts of the electron discharge device by electrolysis, which may be accurately controlled to produce a relatively thin uniform coating of iron in the desired region. This coating does not flake off, is relatively easily outgassed during assembly and evacuation of the device, and is closely controllable as to thickness of the coating whereby the finished dimensions of the parts may be accurately controlled during production. The electrolysis, or electro-plating technique of applying the lossy material, is particularly useful in devices where close tolerances must be maintained, since no mechanical stresses are utilized during application of the lossy material which might deform the parts of the electron discharge device, as is the case when the lossy material is sprayed or painted on the tube elements.

This invention further discloses that the ferro-magnetic lossy coating described above is particularly useful in traveling wave devices utilizing transverse magnetic fields, since the extremely thin coating required to produce the desired loss produces little or no distortion of the magnetic field, as would be the case if larger masses of ferro-magnetic material were applied, for example, by spraying or painting techniques, or by fabricating the tube elements of ferro-magnetic material.

This invention further discloses that the effectiveness of lossy material in the electron discharge device may be further enhanced by making the characteristic impedance of the network structure different in the region thereof containing the lossy material than in the other regions of the network structure where it is desired that the rate of build-up of signal energy be a maximum. Specifi-

2

cally, in traveling wave devices utilizing a backward wave phenomenon wherein the electron stream moves along the slow wave propagating network structure in a direction opposite to the direction of motion of the energy of the signal wave traveling in the network structure but in the same direction as the apparent phase velocity of a component of the wave traveling in the network structure, the lossy material is positioned in the region adjacent one end of a nonreentrant network structure toward which electrons move along paths adjacent the network structure, and signal energy is extracted from the device adjacent the end of the network structure away from which electrons move along paths adjacent the network structure. The impedance of the network structure along the majority of the network structure is made as high as feasible from the standpoint of structural requirements, heat dissipation requirements, and breadth of frequency response characteristics, while the impedance of the network structure on which the lossy material is positioned is made considerably lower, thereby increasing the currents in the walls of the network structure, and hence increasing the absorption coefficient per unit length along the network structure of the lossy material coated thereon.

This invention further discloses a particular structure for lowering the impedance of the network in the region of the lossy material comprising using an interdigital structure for the network. The spacing between adjacent fingers in the network structure is then reduced in the region of the lossy material from the spacing of the fingers throughout the remainder of the network, thereby lowering the characteristic impedance of the network in this region. In order to prevent impedance discontinuities along the network, the lowering of the impedance is accomplished by reducing the spacing of the fingers gradually and by placing lossy material on the fingers in the region where the spacing is being gradually reduced.

This invention further discloses that the network may be nonreentrant, that is, signals traveling along the network do not reenter upon themselves, this being accomplished by a break in the network such that the network has two ends substantially isolated from each other at the frequency of the signals except for the path along the network and except for any coupling which may be achieved from electron streams interacting with the network.

Other and further objects and advantages of this invention will be apparent as the description thereof progresses, reference being had to the accompanying drawings, wherein:

Fig. 1 illustrates a longitudinal cross-sectional view of a linear magnetic backward wave oscillator utilizing the lossy material and impedance transformation features of this invention;

Fig. 2 illustrates a transverse cross-sectional view of the structure shown in Fig. 1 taken along line 2—2 of Fig. 1;

Fig. 3 illustrates a transverse cross-sectional view of a further embodiment of the invention illustrating the features of this invention as applied to a circularly arranged backward wave oscillator utilizing a transverse magnetic field; and

Fig. 4 illustrates a graph showing the attenuation produced by structures of Figs. 1, 2 and 3.

Referring now to Figs. 1 and 2, there is shown an electron discharge device comprising an anode structure 10. Anode structure 10 has a metallic envelope portion made up of a back plate 11, a front plate 12, end plates 13, and side plates 14, which are hermetically sealed together to form an oblong-shaped box. Positioned inside the anode envelope rigidly attached to the back plate 11 and extending the length thereof between end

plates 13 are a pair of spaced, parallel anode support members 15, which are, for example, metal. Each of support members 15 has attached thereto a plurality of anode elements 16, which extend toward the opposite support member 15 from that to which they are attached. The fingers attached to opposite support members 15 overlap to form an interdigital, or folded wave-guide-type of anode network structure. Fingers 16 are spaced from back wall member 11, and the spaces between the end of fingers 16 and the opposite support member 15 from 10 that to which they are attached are made substantially equal to the spaces between adjacent fingers. It is to be clearly understood, however, that other ratios of spacing could be used.

Positioned somewhat beyond one end and in front of the network of fingers 16 is a cathode structure 17, comprising a cathode support member 18, which may be, for example, an annular cylindrical member which extends outwardly through front plate 12 and spaced therefrom. The cathode support member is sealed by means of an insulating seal 19 to a cylindrical member 20, which in turn, is sealed to the aperture in front plate 12 through which support plate member 18 passes. An indirectly heated cathode 21 is shown, by way of example, as being rigidly attached to the inner end of support cylinder 18. Cathode 21 comprises a box-like structure containing a heater wire 22. One end of heater wire 22 is connected to the cathode 21, and the other end thereof is connected to a lead-in member 23 extending outwardly through support cylinder 18, spaced therefrom, and insulatingly sealed to the lower end of support cylinder 18 by an insulating seal 24. The surface of cathode 21, which is presented to the plane containing the tips of the fingers 16, is coated with electron-emissive material 25.

A conductive block 26 attached to the anode structure 10 directly opposite the electron-emissive surface is provided, for the purpose of correctly shaping the electron stream, which, upon the heating of cathode 21, emanates from the electron-emissive coating 25. The electron stream is directed along paths adjacent the front surface of fingers 16 under the influence of transverse electrostatic and magnetic fields. The electrostatic field is produced between said fingers and a sole 27 which is positioned in front of fingers 16 and which is supported on lead-in supports 28 extending out through the front plate 12 and insulated therefrom; the magnetic field transverse to the electrostatic field is produced by means of magnetic pole pieces 28a. The anode structure 10 is maintained positive with respect to the sole electrode 27 and the potential on the cathode structure 17 is adjusted such that electrons emanating from surface 25 will, with the proper polarity of magnetic field produced between pole pieces 28a, travel down the space between fingers 16 and sole 27, whereby signals traveling along the network of fingers 16 will interact with said electrons causing signal amplitude build-up, and, in this case, oscillations.

Attached to the anode finger element 16 nearest cathode structure 17 is a signal output lead 29, which extends outwardly through an aperture in the back plate 11 and forms the central conductor of a coaxial line 30 whose outer conductor 31 is sealed to the back plate 11 at the aperture through which the output lead 29 passes. The lead 29 is insulatingly sealed to the outer conductor 31 by means of a ceramic seal situated inside coaxial line 30 and not illustrated in the drawings. The coaxial line 30 forms a signal output coupling structure from which high frequency energy is extracted from the anode network and fed to any desired load. A signal coupling structure 32 is illustrated herein as being connected to the anode fingers 16 at the other end of the network structure, but may be omitted, if desired, since all the power is extracted from the device by means of the coaxial line 30. Structure 32 may be used, for example, for

measuring reflected energy not absorbed in the tube or for injecting a locking signal.

Lossy material is introduced into the network structure at the end thereof away from the cathode by coating the fingers 16 in this region, for example thirty in number, with such lossy material. The lossy material is applied before assembly of the device by dipping the fingers 16 attached to the support members 15 in an electrolyte solution, which may be, for example, a solution of seventy percent, by weight, of ferrous chloride and thirty percent, by weight, of calcium chloride at a concentration of twenty-two grams per liter of water. An electrode of pure iron is placed in the electrolyte solution and is connected to the positive pole of a voltage source, while the negative pole of a voltage source is connected to the fingers 16 through the anode support members 15. The portion of each support member 15 and the fingers 16 which it is desired not to coat may be kept out of the electrolyte or coated with any desired coating which will prevent a deposit of iron thereon. The coating of pure iron which appears on the fingers 16 is very uniform and the thickness of the coating may be closely controlled by controlling the time and current of the plating process. The coating may be of the order of .001 inch, or less, completely surrounding the appropriate fingers, thereby providing better adherence of the coating than fingers which are partially encased. It has been found that, if fingers and other elements of the anode structure be made of copper, heat generated in the iron coating is easily conducted away, such that lossy material may absorb large amounts of power without difficulty.

In order to increase the effectiveness of absorption of energy in the region of the network structure coated with lossy material, said region being indicated by stippling on the fingers 16, the characteristic impedance of the network is made lower in this region than along the remainder of the network structure which is designed to be the major portion of the network structure. This is accomplished by decreasing the spacing between the fingers in the region. For example, the spaces 33 between the fingers at the end of the network structure away from the cathode structure 17 are much smaller than the spaces 34 between the fingers over the major portion of the anode network, said portion extending to the end of the network structure to which the output coupling structure 30 is connected.

In order to avoid a sharp transition between the high characteristic impedance of the network structure over the major region thereof and the low characteristic impedance in the region thereof containing the lossy material, a transition section is provided also containing lossy material wherein the spaces as shown at 35 gradually decrease from the size of spaces 34 along the network away from the cathode to the size of spaces 33, this transitional section being, for example nine or ten spaces in length. The length of the transitional section is somewhat less than an electrical quarter wave length over the range of desired operating frequencies for the particular device illustrated herein. However, the bandpass of the network structure is sufficiently broad that the spaces 35 have, to some degree, quarter wave impedance transformer characteristics, and the change in spacing between adjacent fingers is adjusted in accordance with the desired impedance thereof if the successive spaces are considered as successive sections in a multi-section quarter-wave impedance transformer. This action is further improved by having the fingers in the transition section also coated with lossy material. While in the device shown herein the pitch distance between adjacent fingers has been held constant and the spacing between fingers adjusted by adjusting the thickness of the fingers, it is to be clearly understood that the spacing between fingers could also be adjusted by maintaining a constant finger thickness and varying the pitch distance between fingers, or by varying both finger thickness and pitch distance, if so desired. It

is also to be clearly understood that the particular lossy material disclosed herein may be used with other impedance transformation structures, or with other anode structures than the interdigital structure, such as helixes, strapped and unstrapped cavity-type network structures, such as those conventionally used in cavity magnetrons, or any other desired signal-wave transmission network. It is to be clearly understood that the lossy material and impedance transformation techniques can also be utilized with traveling wave tubes which do not employ transverse magnetic fields and with traveling wave tubes for amplification as well as oscillation generating purposes.

Referring now to Fig. 3, there is shown a transverse cross-sectional view of a further embodiment of this invention utilizing a signal wave transmission network structure arranged along an arcuate path. The anode structure comprises a hollow metallic cylinder 36 covered by a lower end plate 37 and an upper end plate, not shown. Interdigital fingers 38 are provided for the signal wave transmission network structure, said fingers being attached to support rings 39, which, in turn, are attached to the inner surface of anode cylinder 36. The spacing of the fingers 38 and the mounting thereon with respect to the anode cylinder 36 are similar to that described in connection with fingers 16 of Figs. 1 and 2, the difference being that fingers 38 lie in an arcuate locus, while fingers 16 lie in a linear locus.

Over one portion of the arcuate locus of the network structure, the fingers 38 have been omitted and a conductive member 40 has been substituted, this being securely attached to anode ring 36. Member 40 is dimensioned and positioned such that waves traveling along the network structure are prevented from being coupled between the two ends of the network of members 38, except along the network, so that the network structure is non-reentrant. Also a projection 41 on member 40 prevents electrons, moving along paths adjacent the fingers 38, from traversing the gap between the adjacent ends of the network structure of fingers 38. A signal output coupling device 42 is coupled to the network structure by connecting the center conductor 43 of coupling device 42, which comprises a coaxial conductor, to the end finger of the network of fingers 38 away from which electrons move along the network of fingers 38. Conductor 43 extends outwardly through an aperture in anode cylinder 36 spaced therefrom, and is sealed by means of an insulating seal, not shown, to an outer conductor 44, which, together with an inner conductor 43, makes up the signal output coupling device 42. Device 42 is similar to the device 30 of Fig. 1. The anode fingers 38 at the opposite end of the network structure from the coupling device 42 have the spacing therebetween decreased similar to the manner disclosed in connection with Figs. 1 and 2 and are coated with lossy material in a manner similar to that described in connection with Figs. 1 and 2.

Positioned inside the region defined by fingers 38 is a substantially cylindrical sole structure 45 which is attached by means of a web 46 to a support cylinder 47, which, in turn, is insulatingly supported through the upper end plate by an insulating seal, not shown, in accordance with well-known practice.

A cathode 48 is positioned adjacent the member 40 somewhat beyond the end of network of fingers 38 to which coupling device 42 is connected. Cathode 48, as shown here, is a ribbon extending parallel to the fingers 38 for substantially the same distance parallel to the axis of the tube as the fingers 38. Cathode 48 is held in position by upper and lower cathode support members 49, which are urged apart by spring 49a. Support members 49 are connected through insulating supports indicated diagrammatically at 50 to projections 51 attached to sole 45. A conductive lead-in structure 52 connects one of the cathode support members 49, for example, the upper one, to a lead-in cylindrical member 53, which extends coaxial with cylinder 47 and is sealed thereto

by an insulating seal outside the discharge device in accordance with well-known practice. The other cathode support 49 is connected by means of a conductive lead-in structure, not shown, to a lead-out member 54 positioned inside cylinder 53 coaxial therewith, spaced therefrom, and sealed thereto by an insulating seal outside the discharge device in accordance with well-known practice. A magnetic field is imposed parallel to the axis of cylinders 36, 47 and 53, and, hence, parallel to fingers 38 and cathode 48 in the space between fingers 38 and sole 45 and the space between cathode 48 and member 40. This magnetic field is produced by means of magnetic pole pieces positioned adjacent the outer surfaces of the end plates, including end plate 37, in a similar manner to the application of pole pieces 28a to the device shown in Figs. 1 and 2.

Electrons are emitted from the cathode 48 when a suitable heater current is applied to the cathode 48. Cathode 48 may be any suitable electron-emissive material, such as tungsten or tantalum, or may be coated with electron-emissive material. Electrons emitted from cathode 48 will be directed along paths between the anode signal wave transmission network structure of fingers 38 and the sole 45 in a direction counter-clockwise, for the view shown in Fig. 3, under the influence of an electrostatic field (produced by a voltage impressed on the sole 45, which is negative with respect to the anode 36 and fingers 38, and the above-mentioned magnetic field. Backward wave oscillations developed along the network of fingers have energy components which travel in the opposite direction from the direction of motion of the electrons, and, hence, arrive at the output coupling device 42 whence they are coupled to the desired output load, not shown. Undesired reflections having energy components traveling in the opposite direction, that is, in the same direction as the electron stream, are absorbed by the lossy material coated on the members 38 in the region at the other end of the network of fingers from that to which coupling device 42 is connected.

Referring now to Fig. 4, there is illustrated a graph showing the degree of attenuation which has been achieved with the type of lossy material and network impedance transformation structures disclosed herein. Along the axis of abscissae is plotted frequency in megacycles per second, the region shown here, by way of example, being from 2300 megacycles to 3100 megacycles. Plotted along the axis of ordinates is the attenuation in decibels which is achieved by applying an input signal to the coupling device 42 and measuring, by means of a coupling device connected at the other end of the network of fingers 38, the amount of energy propagated along the network of fingers through the lossy material coated on a portion thereof. The graph of Fig. 4 indicates the attenuation in decibels and shows that at the lower frequency of, for example 2300 megacycles, the network structure has a loss of approximately thirteen decibels, as shown by point 55. The attenuation increases slightly with frequency reaching fifteen decibels at approximately 2700 megacycles, as shown by point 56, and then increases more rapidly reaching a loss of approximately nineteen decibels at 3100 megacycles, as shown at point 54. Thus it may be seen that the network structure illustrated herein has a relatively uniform loss over a relatively wide range of frequencies.

This completes the disclosure of the specific species of the invention illustrated herein. However, many modifications thereof will be apparent to persons skilled in the art without departing from the spirit and scope of the invention. For example, the device shown in Fig. 3 could have a grid positioned over the cathode 48 in order to control the quantity of electrons emitted from the cathode. The device of Fig. 3 could be made with the network of elements on the inside surrounded by the sole and cathode. If so desired, a signal coupling device similar to the device 42 of Fig. 3 could be connected

to the other end of the network of fingers 38 from that to which device 42 is connected for the purpose of injecting a signal for stabilizing, locking, or amplifying purposes. The lossy material in the case of an amplifier could be coated uniformly along the length of network of fingers 38 rather than at one end thereof, the lossy-coating or material may be omitted, and the lowering of the characteristic impedance in the desired region of attenuation may be relied on to produce said attenuation, particularly at the higher frequencies. If desired, a continuous cathode along the entire length of the sole 45 or along any desired portion thereof could be used in place of the point source cathode illustrated herein. Accordingly, it is desired that this invention be not limited by the particular details illustrated herein, except as defined by the appended claims.

What is claimed is:

1. An electron discharge device comprising a source of electrons, a signal wave transmission network structure for propagating electromagnetic wave energy and spaced from said source, means for directing electrons from said source along paths adjacent to said network structure in energy-exchanging relation with said wave energy and signal output means coupled to said network structure adjacent the end thereof from which electrons are emitted, said network structure having a signal absorbing region adjacent said signal output means, and occupying a minor portion of said structure, the characteristic impedance of said network structure being lower in said region than in the remainder of said network structure.

2. An electron discharge device comprising a source of electrons, a signal wave transmission network structure spaced from said source comprising a plurality of substantially non-magnetic interdigital conductive members, and signal absorbing means coupled to a minor portion of said network structure, the characteristic impedance of said network structure being lower in the region of said absorbing means than in the remainder of said network structure, the configuration of said network structure in the region of said absorbing means being progressively varied.

3. A signal wave transmission network structure, and signal absorbing means coupled to a minor portion of said network structure in a region spaced from said signal output means, the characteristic impedance of said network structure being lower in the region of said absorbing means than in the remainder of said network structure.

4. An electron discharge device comprising a source of electrons, a slow wave transmission network structure for propagating wave energy, said network structure having an energy-absorptive region, means for directing electrons from said source along paths adjacent to said network structure and in energy-exchanging relation with said wave energy, the characteristic impedance of the entire absorptive region of said network structure being lower than that of the remainder of said network structure.

5. An electron discharge device comprising a source of electrons, a slow wave transmission network structure for propagating wave energy, means for directing electrons from said source along paths adjacent to said network structure in energy-exchanging relation with said wave energy, said network structure including an energy-absorptive region and a major portion along which the preponderance of energy exchange between said wave energy and said electron beam occurs, the characteristic impedance of said signal-absorptive region of said structure being less than that of said major portion of said structure.

6. An electron discharge device comprising a source of electrons, a non-reentrant slow wave transmission network structure for propagating wave energy, means for directing electrons from said source along paths adjacent

to said network structure in energy-exchanging relation with said wave energy, said network structure including an energy-absorptive region positioned adjacent the end of said network structure toward which electrons move along said paths, and a major region along which the preponderance of energy exchange between said wave energy and said electron beam occurs, the characteristic impedance of said signal-absorptive region of said structure being less than that of said major region of said structure.

7. An electron discharge device comprising a source of electrons, a slow wave transmission network structure for propagating wave energy, means for directing electrons from said source along paths adjacent to said network structure in energy-exchanging relation with said wave energy, said network structure including an energy-absorptive region at least a portion of which is of substantially uniform impedance and a major region along which the preponderance of energy exchange between said wave energy and said electron beam occurs, the characteristic impedance of said signal-absorptive region being less than that of said major region.

8. An electron discharge device comprising a source of electrons, a slow wave transmission network structure for propagating wave energy, means for directing electrons from said source along paths adjacent to said network structure and in energy-exchanging relation with said wave energy, said network structure comprising an energy-absorptive region including a plurality of spaced conductive members of uniform pitch, said network structure further including a major portion along which the preponderance of energy exchange between the wave energy and the electron beam occurs, the conductive members of said energy-absorptive region having disposed thereon lossy material, the spacing between adjacent ones of said members being less in the region of said lossy material than along said major portion of said network structure, whereby the characteristic impedance of said energy-absorptive region is less than that of said major portion of said network structure.

9. An electron discharge device comprising a source of electrons, a slow wave transmission network structure for propagating wave energy, means for directing electrons from said source along paths adjacent to said network structure and in energy-exchanging relation with said wave energy, said network structure comprising an energy-absorptive region including a plurality of spaced conductive members of uniform thickness, said network structure further including a major portion along which the preponderance of energy exchange between the wave energy and the electron beam occurs, the conductive members of said energy-absorptive region having disposed thereon lossy material, the pitch of said network structure being less than in the region of said lossy material than along said major portion of said network structure, whereby the characteristic impedance of said energy-absorptive region is less than that of said major portion of said network structure.

10. An electron discharge device comprising a source of electrons, a slow wave transmission network structure for propagating wave energy, means for directing electrons from said source along paths adjacent to said network structure and in energy-exchanging relation with said wave energy, said network structure comprising a plurality of spaced conductive members, said network structure including an energy-absorptive region at least a portion of which is of substantially uniform impedance and a major portion along which the preponderance of energy exchange between the wave energy and the electron beam occurs, the conductive members of said energy-absorptive region having disposed thereon lossy material, the characteristic impedance of said energy-absorptive region of said structure being less than that of said major portion of said structure.

11. An electron discharge device according to claim 7

wherein the construction of the network structure in the energy-absorptive region is progressively altered to provide an impedance match between said portion of said signal-absorptive region of substantially uniform impedance and the major portion of said network structure.

12. An electron discharge device according to claim 10 wherein the construction of a portion of the members of the network structure in the energy-absorptive region is progressively altered to provide an impedance match between said portion of said signal-absorptive region of substantially uniform impedance and the major portion of said network structure.
